UNITED STATES PATENT OFFICE.

CHARLES M. CRANE, OF CANTON, OHIO, ASSIGNOR TO THE GILLIAM MANUFACTURING COMPANY, OF SAME PLACE.

DESIGN FOR A PAD-PLATE.

SPECIFICATION forming part of Design No. 30,275, dated February 28, 1899.

Application filed February 4, 1899. Serial No. 704,589. Term of patent 14 years.

To all whom it may concern:

Be it known that I, CHARLES M. CRANE, a citizen of the United States, residing at Canton, Stark county, Ohio, have invented and produced a new and original Design for Pad-Plates, of which the following is a specification, reference being had to the accompanying drawings, forming a part thereof.

Figure 1 is a rear view of a pad-plate, showing my new design; and Fig. 2 is a transverse sectional view taken on line 2 2 of Fig. 1.

As shown in the drawings, the leading or material features of my design consist of the curved form of a pad-plate having upwardly-extended flanges on its front and rear edges—that is to say, the flanged plate is curved at its middle, substantially as shown—whereby the parts or wings B B' lie at an angle to each other of approximately ninety degrees, and each flanged wing is, when viewed from the front or rear, of double-ogee form, the top thereof adjacent to the middle of the plate being convex and at the middle part of the wing

being concave and at and near its lower end being convex. A substantially horizontal loop D extends rearward from the middle of the plate. The flanges on the edges of the plate are indicated by C C. The parts of each wing which when viewed from above are convex and concave, as stated, are indicated by the following letters, viz: the convex part of each wing near the middle of the plate by b, the concave middle part of each wing by b', and the convex part of each wing at or near its end by b².

Having described my invention, what I claim as new, and desire to secure by Letters Patent, is—

The design for a pad-plate as herein shown and described.

In testimony whereof I hereunto affix my signature in the presence of two witnesses:

C. M. CRANE.
